(57) CLAIM

The ornamental design for a garden torch lamp, as shown and described.

DESCRIPTION

FIG. 1 is a perspective view of the garden torch lamp showing my new design;

FIG. 2 is a bottom plan view thereof;

FIG. 3 is a top plan view thereof;

FIG. 4 is a left side elevational view thereof;

FIG. 5 is a right side elevational view thereof;

FIG. 6 is a front elevation view thereof; and,

FIG. 7 is a top plan view thereof.

The broken lines shown on the drawings depict portions of the garden torch lamp that form no part of the claimed design.
